UNITED STATES PATENT OFFICE.

JOSEPH W. WIGNER, OF WABASH, INDIANA.

BURGLAR-ALARM.

SPECIFICATION forming part of Letters Patent No. 634,635, dated October 10, 1899.

Application filed April 11, 1899. Serial No. 712,608. (No model.)

To all whom it may concern:

Be it known that I, JOSEPH W. WIGNER, a citizen of the United States, residing at Wabash, in the county of Wabash and State of Indiana, have invented certain new and useful 5 Improvements in Door-Closers and Alarms, of which the following is a specification.

My invention relates to door-closers and alarms, and has for its object to provide an 10 improved device of this class.

With this object in view the invention consists in the improved construction, arrangement, and combination of parts hereinafter fully described and afterward specifically 15 pointed out in the claim.

The accompanying drawing is a perspective view of the invention, the door being shown partially open and the position of the weight indicated in dotted lines.

Referring to the drawing by letters, A indicates a door-frame, and B a screen-door hinged thereto. C indicates a bracket secured to the upper edge of the door near its outer side, having a horizontal arm C' at 20 right angles to the face of the door and an upright arm C'' in the same plane as arm C' and at right angles thereto. A cord D, secured to arm C'', leads around a pulley E, journaled on the door-frame A, thence 25 along the door-frame and around a pulley F, and finally downward and carrying a weight G at its lower end arranged to slide in a tubular casing H, secured to the frame. A crank-pin I projects from the pulley F, to 30 which is attached a spring-arm J, which 35 passes up through an opening in an angular

bracket K, secured to the frame, and carries at its upper end a bell L.

When the door is opened, the cord will rotate the pulleys, and the pulley F, with its 40 crank-pin, will oscillate the arm J and ring the bell L, and the weight G will draw the cord back, closing the door, rotating the pulleys in the opposite direction, and continuing the ringing of the bell. 45

From the foregoing it will be apparent that I have provided simple, inexpensive, and efficient means whereby when a door is closed or opened it will rotate a pulley, and the rotation of the pulley will cause the sounding 50 of an alarm.

It will be understood by those skilled in the art that a variety of changes in or variations from the constructions described and illustrated may be made without departing from 55 the spirit and scope of my invention.

Having thus fully described my invention, what I claim as new, and desire to secure by Letters Patent of the United States, is—

The combination with a door, a pulley, a 60 cord attached to the door and passing over the pulley, and a weight on the cord, of a crank-pin on the pulley and a spring bell-ringing arm pivoted on the crank-pin, substantially as described. 65

In testimony whereof I affix my signature in presence of two witnesses.

JOSEPH W. WIGNER.
